UNITED STATES PATENT OFFICE

BERT E. MILLS, OF OAK PARK, ILLINOIS, ASSIGNOR TO MILLS NOVELTY COMPANY, OF CHICAGO, ILLINOIS, A CORPORATION OF ILLINOIS

MUSIC-ROLL-CORRECTING MACHINE

Application filed September 16, 1927. Serial No. 219,869.

This invention relates to apparatus for preparing master rolls for use in the manufacture of perforated paper music rolls for automatic musical instruments and has for its object the provision of an editing or correcting machine for detecting and correcting errors which may have occurred in perforating the master rolls.

The invention resides in the mechanism and in the method whereby this object is obtained.

Other features and advantages of the invention will be apparent as it is better understood from the following description, which, taken in connection with the accompanying drawings, discloses a preferred embodiment thereof.

Referring to the drawings,

Figure 1 is a side elevation of a machine in which my invention is embodied;

Fig. 2 is a front elevation thereof;

Fig. 3 is a front-to-back sectional view of the upper part of the machine, certain parts being broken away for convenience in illustration;

Fig. 4 is a detail sectional view of certain of the parts shown in Fig. 3, showing the player contact brush in engagement with the contact roll through a perforation in the music sheet;

Fig. 5 is a wiring diagram and diagrammatic view of certain of the parts of the mechanism; and

Fig. 6 is a plan view of the scale used in correcting the music sheets.

The machine as illustrated comprises an inclined upper frame part 21, substantially like a desk or table top, at which the operator may work, said frame part carrying certain of the operating elements of the machine and being supported by an under framework consisting of front vertical uprights 22, rear inclined uprights 23 and braces 24 and 25.

Bearings 26 and 27 are provided on the upper part of the table 21 for a reel shaft or spindle 28, adapted to releasably support a reel 29, upon which the music sheet to be edited is wound, the reel being adapted to be clamped in place by means of a hand screw 31, shown

in Fig. 2 of the drawings, and the reel shaft being adapted to be driven by means of a pulley 32 on the end thereof and a belt 33, taking over said pulley and over a pulley 34 on an intermediate drive shaft 35 carrying a large pulley 36 adapted to be driven by a belt 37, in turn driven from an armature shaft 38 of an electric motor 39, supported upon the cross brace 24. The shaft 35 has bearings in depending brackets 42 on the underside of 60 the table 21.

Referring now to Fig. 3, it will be noted that the music sheet, which is indicated by the reference character 43, is led from the reel 29 through an opening 44 in the table, over a contact roll 45, a guide board 46 and a guide roll 47 and is wound onto a reel 48, mounted beneath the table upon a reel shaft or spindle 49 having bearings 51 and 52 in brackets 53 and 54 depending from the front 70 part of the table 21. A clamp screw 55, similar to the screw 31 for the upper reel, is employed for clamping the reel 48 in place and the reel shaft 49 is adapted to be rotated by means of a pulley 56, loosely mounted on the outer end thereof and adapted to be operatively connected thereto by means of a clutch 57, said pulley being driven by means of a belt 58 extending over a drive pulley 59 on a short shaft 61, mounted in a bearing 62 in 80 a bracket 63 at the side of the frame, said shaft 61 carrying a worm wheel 64, meshing with a worm 65 secured to the shaft 66 of a motor 67 supported from the frame at the side of the machine, said motor shaft carrying a fly wheel 68. It will thus be seen that the music sheet may be positively fed in either direction, being fed forwardly by the motor 67 and driving elements hereinbefore described and being reversed by use of the motor 39 and associated driving elements for rotating the reel 29.

Player mechanism is provided in conjunction with the feeding elements above described and consists of a contact roll 45 and wire or brush contacts 71, electrically connected with an automatic musical instrument, such as a piano or violin, operated electrical- 95 ly in known manner. The contact elements 100

71 are carried by a bar 72 provided with a rearwardly extending arm 73, pivoted at 74 to the frame and rigidly connected with a link 75, in turn connected with a vertical connecting rod 76, secured at its lower end to a rearward extension 77 of a foot lever 78, pivotally connected at 80 with a frame part 80', said lever having a pedal 79 at its forward end and being normally held in raised position by means of a spring 81, connecting said lever to the frame. Thus when it is desired to operate the machine, the operator places his foot upon the pedal 79, thereby establishing contact between the roll 45 and contact wires or brushes 71, as shown in Fig. 4, which results in playing the instrument when the music roll is fed between said contact elements, it being understood that the paper serves to insulate the contacts, except at the points where the perforations permit the contact elements 71 to engage the roll 45.

It will be noted, from Figs. 2 and 6 of the drawings, that I employ a scale 82, bearing indicia of the notes of the instrument, or instruments, for which the music roll is intended, these being so spaced and numbered as to facilitate identification of the perforations in the sheet with the notes played thereby. The scale shown is prepared for a roll 30 perforated for both piano and violin and contains, in addition to the notes played on the various keys and strings, certain spaces identified with perforations for producing various tone effects and controls.

35 Referring now to Fig. 5 of the drawings, the electric control of the machine will be described. The contact roll 45 is connected by a wire 83 with the positive side of an electric current supply line.

40 The contact brushes 71 are connected by a series of wires 89 and 91, respectively, with magnets 87 and 88 of an electric piano and an electric violin (either or both may be used) and said magnets are in turn connected with 45 the negative side of the line through a three-way switch 92. Thus when the foot pedal 79 is depressed and the contact brushes 71 moved to the down position, the player mechanism is ready to operate when the music roll is fed 50 over the roll 45.

55 As previously explained, the music rolls are fed forwardly by the motor 67. The latter is connected with the negative side of the line by a wire 67', variable resistance 86 being interposed between the line and the motor whereby the speed of the latter may be controlled. The motor 67 is connected by a wire 70 with a contact element 104 carried by and insulated from the brush carrier bar 60 72. Said contact element 104 is adapted to engage a contact element 103 on the frame when the bar 72 is in the down position. The contact element 103 is connected by a wire 100 with a switch 85, connecting with the positive side of the line. Thus when the switch

85 is closed and the contact 104, 103 is made by lowering the bar 72, the motor 67 will be energized and the music roll fed forwardly by means of the instrumentalities previously described.

70 When a false note is detected, the forward feed may be stopped by releasing the foot lever 79, thus breaking the contact 104, 103. This makes contact between two contact elements 107 and 108 carried respectively upon the frame and the bar 72 and properly insulated. The contact 108 is connected by a wire 84 with the negative side of the line and the contact 107 by a wire 102 with the motor 39, which in turn is connected by a wire 101 80 with one side of a switch 98, 99, the other side of which is connected with the main switch 85. The switch 98, 99 is adapted to be closed by means of a lever 93, pivoted at 94 to the frame and carrying a screw 97 at the end thereof adapted to engage the contact 98, which is spring-mounted and adapted to be thus pressed into engagement with the contact 99, thereby connecting the motor 39 with the positive side of the circuit.

90 The lever 93 carries a pin 95, engaging in an annular groove in a clutch element 96 of the clutch 57 and is primarily for the purpose of opening and closing said clutch. It also serves, however, to control the switch 98, 99 so that the latter is always open when the clutch is closed and always closed when the clutch is open. This prevents energizing the reversing motor 39 when the motor 67 is connected for operation of the forward feed 100 and it will also be noted that the motor 39 cannot be energized except when the bar 72 and brushes 71 are raised, as it is only then that the switch 107, 108 is closed. This prevents tearing the paper by driving the roll 105 in reverse direction with the brushes down.

The motor 39, when energized, drives a reel 29, through the connections hereinbefore described, thereby reversing the direction of travel of the music sheet until the defective perforation which caused the false note is arranged at desired position, which, as shown, would be at substantially the center of the guide board 46. The guide board at this point is perforated, as indicated at 110 105, and perforators 106 are arranged above this point in the board so that the defective perforation may be corrected (which may be done by the perforators alone or by pasting over the defective perforation and making a new one). The corrected portion of the sheet is preferably then carried back beyond the roll 45 and the sheet again fed forwardly so as to determine whether or not the defect has been properly corrected and, if so, the sheet continues until another false note is detected, at which time the forward feed is stopped and the reversing motor connected into the circuit by operation of the clutch throw-out and switch lever 93, the correcting 115 120 125 130 135 140 145 150 155 160 165 170 175 180 185 190 195 200 205 210 215 220 225 230 235 240 245 250 255 260 265 270 275 280 285 290 295 300 305 310 315 320 9860 9865 9870 9875 9880 9885 9890 9895 9900 9905 9910 9915 9920 9925 9930 99

operation just described being then repeated.

After the roll has been edited and corrected in the manner described, the corrected roll may be removed and a new, full roll placed in the upper position. The sheet or web therefrom is threaded through the table 21 over the contact roll 45, guide board 46 and guide roll 47 to the lower receiving reel, whereupon the machine is in condition for correcting the new roll. It will be observed that the scale 82 is mounted on a pivoted board 107, provided with knobs 108, whereby it may be raised and lowered.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A music roll correcting machine comprising means for rotatably supporting music rolls in spaced relationship, electric player mechanism intermediate said rolls and through which the music sheet is adapted to pass, and a sheet support beyond said mechanism and over which the music sheet is adapted to be directed with a substantial area thereof presented to the view of the operator in accessible position for correction in the event that a false note is detected in the playing of the piece as the sheet passes through said player mechanism.

2. A music roll correcting machine comprising means for rotatably supporting music rolls in spaced relationship, electric player mechanism intermediate said rolls and through which the music sheet is adapted to pass, a sheet support beyond said mechanism and over which the music sheet is adapted to be directed with a substantial area thereof presented to the view of the operator in accessible position for correction in the event that a false note is detected in the playing of the piece as the sheet passes through said player mechanism, and separate motors for driving said rolls whereby the sheet may be fed forwardly or in reverse direction to a desired point for correction of the false note.

3. A music roll correcting machine comprising means for rotatably supporting music rolls in spaced relationship, electric player mechanism intermediate said rolls and through which the music sheet is adapted to pass, a sheet support beyond said mechanism and over which the music sheet is adapted to be directed with a substantial area thereof presented to the view of the operator in accessible position for correction in the event that a false note is detected in

the playing of the piece as the sheet passes through said player mechanism, separate motors for driving said rolls whereby the sheet may be fed forwardly or in reverse direction to a desired point for correction of the false note, and means rendering the forward feed motor ineffective when the reversing motor is operating.

4. A music roll correcting machine comprising means for rotatably supporting music rolls in spaced relationship, electric player mechanism intermediate said rolls and through which the music sheet is adapted to pass, a sheet support beyond said mechanism and over which the music sheet is adapted to be directed with a substantial area thereof presented to the view of the operator in accessible position for correction in the event that a false note is detected in the playing of the piece as the sheet passes through said player mechanism, separate motors for driving said rolls whereby the sheet may be fed forwardly or in reverse direction to a desired point for correction of the false note, means rendering the forward feed motor ineffective when the reversing motor is operating, and means actuated in the normal operation of said last-mentioned means for completing the reversing motor circuit.

5. A music roll correcting machine comprising means for rotatably supporting music rolls in spaced relationship, electric player mechanism intermediate said rolls and through which the music sheet is adapted to pass, a sheet support beyond said mechanism and over which the music sheet is adapted to be directed with a substantial length and area thereof presented to the view of the operator in accessible position for correction in the event that a false note is detected in the playing of the piece as the sheet passes through said player mechanism, and a perforating device mounted upon the machine for operation upon the sheet at a predetermined point upon said sheet support.

6. A music roll correcting machine comprising means for rotatably supporting music rolls in spaced relationship, electric player mechanism intermediate said rolls and through which the music sheet is adapted to pass, a sheet support beyond said mechanism and over which the music sheet is adapted to be directed with a substantial length and area thereof presented to the view of the operator in accessible position for correction in the event that a false note is detected in the playing of the piece as the sheet passes through said player mechanism, and a scale mounted in visible position and in predetermined relation to the music sheet as the same passes over said sheet support, said scale indicating the notes of the instrument for which the music roll is intended and being graduated to correspond to the perforations in the sheet.

7. A music roll correcting machine comprising means for rotatably supporting music rolls in spaced relationship, electric player mechanism intermediate said rolls and through which the music sheet is adapted to pass, and a sheet support beyond said mechanism and over which the music sheet is adapted to be directed with a substantial length and area thereof presented to the view of the operator in accessible position for correction in the event that a false note is detected in the playing of the piece as the sheet passes through said player mechanism, said player mechanism including contact devices and a musical instrument remotely located and electrically connected therewith.

8. A music roll correcting machine comprising means for rotatably supporting music rolls in spaced relationship, electric player mechanism intermediate said rolls and through which the music sheet is adapted to pass, and a sheet support beyond said mechanism and over which the music sheet is adapted to be directed with a substantial length, and area thereof presented to the view of the operator in accessible position for correction in the event that a false note is detected in the playing of the piece as the sheet passes through said player mechanism, said player mechanism including a plurality of contact devices and a plurality of musical instruments remotely located and electrically connected individually with said contact devices which operate respectively upon different portions of the music sheet as the same is fed from one reel to another.

9. A music roll correcting machine comprising spaced reels from one of which a music sheet is adapted to be unwound and onto the other of which said sheet is adapted to be wound, a support and guide for the sheet between said reels, player mechanism including contact elements disposed between said reels and adapted to make contact through perforations in said sheet, separate motors for driving said reels whereby the sheet may be driven either forwardly or backwardly according to the motor utilized, and means for selectively energizing said motors.

10. A music roll correcting machine comprising spaced reels from one of which a music sheet is adapted to be unwound and onto the other of which said sheet is adapted to be wound, a support and guide for the sheet between said reels, player mechanism including contact elements disposed between said reels and adapted to make contact through perforations in said sheet, separate motors for driving said reels whereby the sheet may be driven either forwardly or backwardly according to the motor utilized, and means for selectively energizing said motors, one of said motors being adapted to operate its reel only when the player contacts are closed and the other of said motors being adapted to

operate its reel only when said player contacts are open.

11. A music roll correcting machine comprising spaced reels from one of which a music sheet is adapted to be unwound and onto the other of which said sheet is adapted to be wound, a support and guide for the sheet between said reels, player mechanism including contact elements disposed between said reels and adapted to make contact through perforations in said sheet, separate motors for driving said reels whereby the sheet may be driven either forwardly or backwardly according to the motor utilized, and means for selectively energizing said motors, said last-mentioned means including devices whereby only one of said motors may be operated at a time.

12. The method of correcting perforated music rolls which consists in feeding the roll from one support to another and through player mechanism disposed between said supports, stopping the forward feed when a false note is detected, reversing the direction of travel of the roll until a desired position is obtained, correcting the perforations in said roll, and thereafter resuming the forward feed whereby the roll is corrected in being transferred from one support to another.

In witness whereof, I hereunto subscribe my name to this specification.

BERT E. MILLS.
